US0D1003579S

(12) United States Design Patent (10) Patent No.: US D1,003,579 S
(45) Date of Patent: * Nov. 7, 2023

(54) FOOTWEAR

(71) Applicant: E.S. Originals, Inc., New York, NY (US)

(72) Inventor: Evan Hoffman, New York, NY (US)

(73) Assignee: E.S. ORIGINALS, INC., New York, NY (US)

() Term: 15 Years

(21) Appl. No.: 29/775,553

(22) Filed: Mar. 24, 2021

(51) LOC (14) Cl. 02-04

(52) U.S. Cl.

USPC D2/923

CLAIM

The ornamental design for a footwear, as shown and described.

DESCRIPTION

FIG. 1 is a perspective view of footwear showing my new design;

FIG. 2 is a top view of the footwear shown in FIG. 1;

FIG. 3 is a bottom view of the footwear shown in FIG. 1;

FIG. 4 is a left side view of the footwear shown in FIG. 1; and,

FIG. 6 is an enlarged rear view of the footwear shown in FIG. 1.

The greyed-out portions bounded by broken lines shown in the drawings represent portions of the footwear that form no part of the claimed design.

1 Claim, 6 Drawing Sheets
